UNITED STATES PATENT OFFICE

HORACE M. HUFFMAN, OF DAYTON, OHIO, ASSIGNOR TO THE HUFFMAN MANUFACTURING COMPANY, OF DAYTON, OHIO, A CORPORATION OF OHIO

BURNER FOR BLOW TORCHES AND THE LIKE

Application filed January 5, 1931. Serial No. 506,675.

This invention relates to burners for blow torches and the like and more particularly to means for pre-heating such a burner to initiate the operation thereof.

The burner of a blow torch as usually constructed, comprises a flame tube which is connected by a conduit with a tank containing liquid fuel under air pressure, the delivery of the fuel from the tank to the flame tube being controlled by a valve at the rear end of the flame tube. The fuel conduit is so arranged with relation to the flame tube that when the burner is in operation the heat therefrom will heat the fuel in the conduit and vaporize the same, but in order to initiate the operation of the burner it has been customary to support a drip cup beneath the burner and to deliver liquid fuel to that drip cup and there ignite the same. The fuel is delivered to the drip cup from the flame tube and in practice the operator opens the controlling valve and places his hand over the end of the flame tube to prevent the escape of fuel therefrom, thus causing the fuel to accumulate in the flame tube and escape therefrom through an opening to the drip cup. This method of filling the drip cup is open to various objections. For example, it not infrequently happens that the burning of the fuel in the drip cup will not sufficiently heat the burner to initiate the operation thereof, and it is necessary to again fill the drip cup and ignite the fuel therein. While the burning of the first cup of fuel may not have heated the burner sufficiently to initiate its operation it will nevertheless have heated the flame tube to such an extent that the operator cannot again place his hand against the end thereof, and in order to fill the drip cup the second time he must find some other means for closing the end of the flame tube. Under many conditions of operation no such means is available and much loss of time and inconvenience is occasioned when the burning of the first cup of fuel fails to set the burner in operation. Further, if the operator wears a glove on the hand which closes the flame tube that glove becomes saturated with fuel

and there is serious danger of its being ignited by the flame from the drip cup.

One object of the present invention is to provide a burner of this kind having improved means for filling the drip cup, which will be free from the objections to the present burner.

A further object of the invention is to provide a burner with means for filling the drip cup which will be very simple in its construction and operation and which can be embodied in the burner at a very low cost.

Other objects of the invention will appear as the device is described in detail.

In the accompanying drawing Fig. 1 is a side elevation of a burner embodying my invention, showing the flame tube and conduit in section; Fig. 2 is a side elevation, partly in section, of a slightly modified form of burner; Fig. 3 is a side elevation, partly in section, of a further modification of the invention; Fig. 4 is a side elevation, partly in section, of a portion of a burner illustrating another embodiment of the invention; and Fig. 5 is a section taken on the line 5-5 of Fig. 4.

In the drawing I have illustrated certain embodiments of the invention but it will be understood that these particular embodiments have been chosen for the purposes of illustration only, and that the invention may take various forms and may be applied to burners of various kinds.

In that embodiment of the invention illustrated in Fig. 1 the preheating device is applied to a well known type of burner head in which the burner proper is in the form of a flame tube 5 and is connected with a source of fuel supply by a vein tube or fuel conduit formed in the burner head and having a horizontal portion 6 and an upright portion 7, the latter portion communicating with the flame tube through an inlet port 8, which is shaped to form a valve seat with which cooperates a needle valve 9 having an operating handle or hand wheel 10. The horizontal portion 6 of the conduit is connected with a tubular fitting 11 which forms a part of the fuel conduit and is attached to and communicates with a fuel tank 12 and which, in

the present instance, forms a support for the burner head or structure. The fuel tank 12 is usually provided with an air pump 13 to subject the fuel therein to air pressure. Arranged beneath the burner and, preferably mounted on the tubular fitting 11, is a drip cup 14. The conduit which delivers the fuel from the tank 12 to the flame tube is provided in advance of the valve 9 with a valve 16 controlled passageway or supplemental conduit through which fuel may be delivered from the conduit to the drip cup. This passageway may take various forms and may be arranged in various positions but, as shown in Fig. 1, the main fuel conduit is formed in the burner structure or head and the burner head is provided with a rearwardly extending part or boss 15 having a longitudinal bore or conduit 16 arranged in line with the horizontal portion 6 of the main conduit, having an outlet 17 directed toward the fuel cup 14 and constituting a supplemental fuel conduit. The bore 16 of the supplemental conduit is provided between a 25 the outlet 17 and the main conduit with a valve seat 18 which is engaged by a valve 19. As here shown, the valve 19 is carried by a stem 20 having screw threaded engagement with the rear portion of the boss 15 and is 30 provided with an operating handle or knob 21. To fill the drip cup it is only necessary to see that the valve 9 is closed and to then open the valve 19 to permit the fuel to flow from the main conduit through the supplemental conduit and its outlet into the drip cup. When the drip cup has been filled the supplemental valve is closed and the fuel ignited. When the burner has been heated the main valve 9 is gradually opened to permit the fuel to enter the flame tube from the main conduit, where it is ignited. Preferably the bore 16 of the supplemental conduit is connected with the main conduit by an orifice 22 of small capacity so that the fuel will be delivered to the outlet 17 for the supplemental conduit at a lowered pressure which will prevent the splashing of the fuel from the drip cup. Further, the pressure on the fuel within the supplemental conduit is reduced to such an extent that there is little likelihood of leakage about the threaded valve stem 20, thus avoiding the necessity of a packing gland at that point. It will be understood, however, that the restricted orifice between the supplemental conduit and the main conduit is not essential to the operation of the device. When the burner head is arranged in an inclined position as shown in Fig. 1, it is desirable that it should be provided with a hollow boss surrounding the outlet opening from the conduit and forming a continuation of the outlet, to prevent the liquid from flowing rearwardly along the outside of the part 55 15 of the burner head.

In Fig. 2 the arrangement is much the same as that shown in Fig. 1 but the supplemental conduit is formed in a separate part, thus making it possible to apply the invention to a burner of the present type without substantial change in the construction thereof. As there shown, the supplemental conduit is formed in a tubular member 23 having at its forward end a threaded projection 24 adapted to be screwed into a threaded opening at the rear end of the horizontal portion 6 of the main conduit. In some burners this horizontal portion of the conduit is bored from the rear end of the burner structure and the rear end thereof closed by a plug. In such a case the plug may be removed and the tubular member 23 substituted therefor. If the main conduit was not bored through the rear end of the burner structure it is only necessary to provide a threaded opening at this point. The supplemental conduit in the tubular member 23 is similar to that shown in Fig. 1 and is connected with the main conduit by a restricted orifice 25 and has an outlet 26 arranged above the drip cup 14. A valve 27 engages a valve seat at the rear end of the restricted orifice 25 to control the flow of fuel to the outlet and this valve is carried by a stem 28 which is screw threaded into the rear end of the tubular member and provided with an operating handle 29.

In Fig. 3 I have shown the invention as applied to a burner of a slightly different type. As there shown, the horizontal portion 30 of the conduit projects rearwardly some distance beyond the flame tube 31 and the upright portion 32 of the conduit is formed in a projection 33 near the rear end of the burner structure and the outlet 34 through which the fuel is delivered from the conduit to the flame tube is spaced some distance from the rear end of the flame tube, the latter having a relatively large opening 35 through which the fuel may enter the flame tube. In this construction the burner structure extends rearwardly to such a point that it is not feasible to further extend the same for the purpose of providing a supplemental conduit. I have therefore provided the lower part of the structure with an enlargement 36, arranged below the horizontal portion 30 of the main conduit, and have formed the supplemental conduit 37 in this enlarged portion of the structure. The forward end of the supplemental conduit is connected by a restricted orifice 38 with a passageway 39 leading to the main conduit. The supplemental conduit also has an outlet 40 directed toward the fuel cup 14 and has between the outlet 40 and the orifice 38 a valve seat which is engaged by a valve 41 which is carried by a stem 42 extending rearwardly beyond the burner structure.

That embodiment of the invention shown

in Figs. 4 and 5 is applied to a burner similar to that shown in Fig. 3 and the supplemental conduit comprises an inclined passageway 43 formed in the burner structure, 5 communicating with the main fuel conduit near the upper end of the tubular member 11 and having its outer end arranged to discharge into the drip cup 14. A valve 44 controls the flow of fuel through the supplemental conduit or passageway.

While I have shown and described certain embodiments of my invention I wish it to be understood that I do not desire to be limited to the details thereof as various 15 modifications may occur to a person skilled in the art.

Having now fully described my invention, what I claim as new and desire to secure by Letters Patent, is:

20 1. In a blow torch, a burner head having a flame 2, a main conduit to connect said flame tube with a source of supply for fuel under pressure, a supplemental conduit having a downwardly directed outlet, 25 and an orifice connecting said supplemental conduit with said main conduit, said orifice being of less capacity than said outlet, a valve to control the flow of fuel through said orifice, a drip cup arranged beneath 30 said outlet to receive fuel therefrom, and a valve to control the delivery of fuel from said main conduit to said flame tube.

2. In a blow torch, a burner head having a flame tube, a main conduit to connect 35 said flame tube with a source of supply of fuel under pressure, a supplemental con-

duit having a downwardly directed outlet, an orifice connecting said supplemental conduit with said main conduit, said orifice being of less capacity than said outlet, and a valve seat interposed between said orifice and said outlet, said burner head also having a screw threaded opening leading to said supplemental conduit, a screw threaded valve stem mounted in said opening, a valve member connected with said stem and movable thereby into and out of engagement with said valve seat, a drip cup supported beneath said outlet to receive fuel therefrom, and a valve to control the delivery 75 of fuel from said main conduit to said flame tube.

3. In a blow torch, a burner head having a flame tube, a main conduit extending lengthwise of said burner head and communicating with a source of supply for fuel under pressure, valve controlled means to connect said conduit with said flame tube, a supplemental conduit substantially in line with said main conduit and having a downwardly directed outlet, an orifice connecting 85 said main conduit with said supplemental conduit, and a valve seat at that end of said orifice adjacent to said supplemental conduit, said orifice being of less capacity than said outlet, a valve stem screw threaded into 90 said burner head in line with said supplemental conduit, a valve member carried by said stem and adapted to engage said valve seat, and a drip cup supported beneath said outlet to receive fuel therefrom.
